DESCRIPTION

5,004,444 A * 4/1991 Chih A63H 5/04
446/406

1. Controller for game device

1.1 : Perspective

1.2 : Front

1.3 : Back

1.4 : Top

1.5 : Bottom

1.6 : Left

1.7 : Right

The thin lines in the representation represent contours only and do not illustrate an ornamentation or decoration on the surface of the product.
